UNITED STATES PATENT OFFICE.

JOHN FRITSCHE, OF PHILADELPHIA, PENNSYLVANIA.

LIQUID-VENDING MACHINE.

1,421,680.

Specification of Letters Patent. Patented July 4, 1922.

Application filed September 16, 1919. Serial No. 324,154.

To all whom it may concern:

Be it known that I, JOHN FRITSCHE, a citizen of the United States, residing in the city and county of Philadelphia, State of Pennsylvania, have invented a new and useful Liquid-Vending Machine, of which the following is a specification.

My present invention comprehends a novel construction of a liquid vending machine 10 wherein a plurality of liquids of a different nature are discharged from the machine upon the insertion of a check or coin of a predetermined denomination.

While my present invention is adapted to 15 vend a plurality of liquids of any desired nature, it has been designed more particularly to be employed in the type of restaurants known as automats, for the vending of coffee and cream.

20 The main object of the invention is to devise a novel construction and arrangement of vending mechanism which is of simple and compact construction, which may be maintained at all times in a sanitary condition,

25 which will employ a minimum number of parts, and which will be of a rigid construction to enable it to withstand the rough usage to which machines of this character are subjected, in practice, by the

30 intending purchasers.

With the above in view my invention further comprehends a novel construction and arrangement of liquid containers, a novel construction and arrangement of measuring 35 devices, a novel construction and arrangement of valve mechanisms and a novel construction and arrangement of coin controlled devices which are collocated and assembled in such a manner that a minimum amount

40 of time is employed in dispensing a plurality of liquids at the same time.

Other novel features of construction and advantage will hereinafter more clearly appear in the detailed description of my invention.

For the purpose of illustrating my invention, I have shown in the accompanying drawings a typical embodiment thereof which is at present preferred by me, since 50 it will be found in practice to give satisfactory and reliable results, although it is to be understood that the various instrumentalities of which my invention consists can be variously arranged and organized and that

55 my invention is not limited to the precise arrangement and organization of these instru-

mentalities as herein shown and described.

Figure 1 represents, in rear elevation, a liquid vending machine, embodying my invention, certain portions thereof being omitted for the sake of clearness of illustration.

Figure 2 represents a section on line 2-2 of Figure 1.

Figure 3 represents a section on line 3-3 of Figure 1.

Figure 4 represents a section on line 4-4 of Figure 2.

Figure 5 represents an end elevation of the coin wheel.

Figure 6 represents a section on line 6-6 of Figure 1.

Figure 7 represents a section on line 7-7 of Figure 6.

Figure 8 represents an end elevation of the construction seen in Figure 7 and showing more particularly the cam for ejecting a coin from the coin wheel.

Figure 9 represents a section on line 9-9 of Figure 1.

Figure 10 represents a section on line 10-10 of Figure 9.

Figure 11 represents a section on line 11-11 of Figure 1.

Figure 12 represents a section on line 12-12 of Figure 11.

Figure 13 represents a sectional elevation of another embodiment of my invention showing the manner in which the size of a measuring cup is varied.

Similar numerals of reference indicate 90 corresponding parts.

Referring to the drawings:

1 designates the supporting frame which carries in any desired manner the liquid container 2 for one type of liquid, as coffee, and 95 the liquid container 3 for the other type of liquid, as cream. The container 2 consists of a double walled container, as will be understood from Figure 2 of the drawings, so that a chamber 4 is formed to receive a 100 temperature changing medium which surrounds the liquid in the inner casing or container 5, in which latter the coffee or other liquid to be dispensed is placed. This container 5 is spaced from the bottom wall of 105 the outer casing or container by means of a tubular spacing element 6 through which passes a fastening device 7 which is connected to the bottom of the outer container in any desired manner.

The fastening device 7, seen in Figure 11, consists of a tubular bolt the head of which

- contacts with the bottom of the inner container 5, while its lower end is in threaded engagement, as at 8, with the externally threaded extension 9 of the valve casing 10.
- 5 The extension 9 passes through the aperture in the bottom of the outer container and is secured in position by means of a nut 11 which is located within the spacing element 6 so as to be out of contact with the temperature changing medium.
- 10 The discharge from the container 2 is through the passage 12 in the fastening device 7. The valve casing 10 is provided with four ports, an inlet port 13, the filling ports 15 14 and 15 and the discharge port 16. Each container 2 is provided with a pair of measuring cups 17 and 18, respectively, and since each of these cups is constructed and connected in a similar manner, a description of 20 one will suffice for both.

Each measuring cup is provided with a laterally extending flange 19 and below this flange the casing is internally threaded as at 20, in order to receive a nut 21 which secures 25 the measuring cup in fixed relation with respect to the bottom plate 22 of the inner casing 5. Each measuring cup is provided with an aperture 23 leading from the measuring chamber proper 24 which latter opens 30 through the upper end of the casing 17. The lower end of the casing 17 rests on the bottom of the outer container and it is internally threaded as at 25, in order to receive the coupling sleeve 26 in threaded engagement 35 with it and provided with a flange 27 which engages the under face of the bottom of the outer container. The threaded sleeve 25 is provided with an exteriorly threaded stem 28 with which engages a coupling nut 40 29. 30 designates a tubular coupling member in threaded engagement with the valve casing 10 and communicating with the port 14 and the passage 26. This coupling member 30 is provided with a conical bearing 45 portion 31 which forms a tight joint with the internal tapered portion 32 of the sleeve 25.

The upper end of the chamber 24 is provided with a closure 33 in threaded engagement with the casing 17, and a gasket 34 is provided in order to seal the joint between such parts. 35 designates a pipe extending through a closure 33 and above the level of the liquid in the inner container 5 to form 55 a vent.

The capacity of the measuring chamber 24 may be increased by recessing the closure 33, as indicated at 36, or it may be decreased by forming on the closure a downward extension or enlargement as 37, see Figure 13.

It will be seen from this that by simply substituting one closure for another the capacity of any measuring chamber 24 may be increased or diminished in accordance with 60 requirements and conditions met with in the

practical operation of the liquid vending machine.

The valve casing 10, see more particularly Figure 12, is provided with a conical valve seat 38 in order to adapt it to receive a conical valve 39 which latter is provided with the ports 40 and 41 which are disposed in such a manner that the ends of each port are 90° apart so that when the port 30, for example, is in communication with the ports 75 13 and 14, the port 41 will be in communication with the ports 15 and 16, see more particularly Figure 11.

The valve casing 10 on opposite sides of the seat 38 is provided with an annular bore 80 42 opening through its juxtaposed walls. The stem of the valve 39 which extends into the chamber 42 is provided with a ball bearing 43 which is secured in position by means of the nuts 44 one of which serves as a lock 85 nut. The ball bearing 43 abuts against a shoulder 45. The chamber 42 is closed by means of a plate 46 secured to the casing in any desired manner. The stem of the valve which extends into the chamber 42 has passing transversely through it a pin 47 which is adapted to engage the walls of the slots 48 in a coupling sleeve 49 on which latter is mounted a ball bearing 50. The coupling sleeve 49 is connected to a shaft 51 which 90 passes through a closure 52 secured to the casing 10 in any desired manner and closing the outer end of the chamber 42. The shaft 51 has fixed to it a gear 53 which meshes with a gear 54 mounted on a shaft 55 journaled in the framework of the machine, see more particularly Figure 1.

The liquid container 2 is provided with an inlet pipe 56 and a discharge pipe 57 which communicate with the chamber 4 in order 105 that a circulation of the temperature changing medium may be effected.

The liquid container 2 is provided with a removable closure 58 and also with a filling port 59 so that the chamber 4 may be filled 110 when desired by pouring the temperature changing medium into the filling port 59. A gage 60 is preferably provided by means of which the height of liquid in the container 4 may be determined and a gage 61 is preferably provided by means of which the height of the liquid in the container 5 may be determined. Each of these gages is preferably provided in the usual manner with a drain cock.

The source of heat such as, for example, a gas burner 62, see Figure 2, is positioned beneath the container 2 so that the temperature changing medium 4 may be maintained at a desired temperature.

The liquid container 3 which is to receive the cream is preferably a double walled container provided with a removable closure 63 and the chamber 64 between the inner container 65 and the outer 130

5 container 66, see Figure 9, is preferably packed with insulating material such as for example cork, although as will be apparent a temperature changing medium can be placed in this chamber 64 if desired. The liquid container 3 is provided in a similar manner to the liquid container 2 with measuring cups 67 and 68 which are constructed and arranged in a similar manner 10 as the measuring cups 17 and 18 in the liquid container 2. A detailed description of them is therefore thought to be unnecessary. The measuring cup 67 is provided with a vented closure 69 and the measuring cup 68 is provided with a vented closure 70. The passage 71 through the fastening device communicates with the port 72 in the valve casing 73 and the valve casing is provided with a port 74 in communication with the 15 measuring cup 67 and with a port 75 in communication with the measuring cup 68. The valve casing 73 is also provided with a discharge port 76.

20 The valve casing 73 is provided with a conically shaped seat 77 with which a conical valve 78 co-operates said valve having ports 25 79 and 80, respectively. The ends of the port 79 open through the valve body at substantially 90° from each other and the same 30 holds true of the ends of the ports 80. It will be apparent to any one that if these vented closures are removed and a cleaning liquid inserted into the inner casing, it will pass through the measuring cups and the 35 valve from such inner casing.

40 The forward end of the stem 48 has mounted on it a ball bearing 81 secured in position by means of nuts 82 one of which serves as a lock nut. The valve stem at the opposite end of the valve 78 has mounted on it a ball bearing 83 and the free end of the stem is slotted as indicated at 84 in order to engage a keyed portion of the shaft 55, see Figure 1. It will be understood 45 from Figure 10 that the valve casing 73 is provided on opposite sides of the valve seat 77 with conically shaped recesses which conform to similar recesses in the valve casing 10 and closures are provided for the open 50 ends of such recesses. 85 designates a discharge pipe which is secured by means of a coupling nut 86 to the valve casing 10. 87 designates a corresponding discharge pipe which is secured by means of a coupling 88 55 to the valve casing 73. These two discharge pipes 85 and 87 extend through an aperture 89 in the front plate 90 of the machine and their discharge ends are located within an ornamental head 91 secured to the 60 front plate of the vending machine.

The coin mechanism.

65 The front plate 90 of the machine is provided with a coin slot 92 which is of the proper dimensions to receive a coin of pre-

determined size and the coin after passing through the coin slot 91 passes into a coin chute 93 which is provided with a movable side 94, see Figure 3, and if the coin is of the proper dimensions it passes through the 70 coin chute and is received in one of the slots 95 in a coin retainer in the form of a coin wheel 96 which is mounted on the shaft 55 so that when the coin chute is partially rotated the shaft 55 will be correspondingly 75 rotated.

76 The coin wheel 96 is recessed, as indicated at 97, in proximity to each coin slot and with the walls of these recesses 97 a spring pressed plunger 98 is adapted to engage and 80 lock the coin wheel in position at predetermined intervals. The plunger 98 is mounted in a recess 99 in a portion of the coin chute 93 and between the bottom wall of this recess and the head of the plunger 85 is interposed a spring 100. The plunger 98 is provided with a threaded stem 101 which carries a nut 102 which is adapted to abut against a fixed portion of the bracket 103 which is carried by the framework of 90 the machine in any desired manner.

104 designates a plate secured to the coin chute 93 to prevent the coin from discharging from the coin wheel until the proper time. The coin wheel 96 is recessed at its 95 periphery, as at 105, to permit the cam 106 on the cam disc 107 to move therein in the path of a coin retained in a slot 95. The coin wheel 96 is fixedly mounted on the shaft 55.

100 The cam disc 107 is loosely mounted on the shaft 55 and is provided near its periphery with a cam 108 which travels in the path of a roller 109 carried by the movable side of the coin chute so that when the cam 105 108 is partially rotated the movable side 94 of the coin chute 93 will open and permit any coin retained therein to drop into the return chute 110 and pass into the cup 111 which is in a position accessible to the 110 intending purchaser. The disc 107 has secured to it a gear 112 which meshes with a gear 113 on a rock shaft 114 which extends through the front plate of the machine and is provided with a grasping handle 115. 115 The rock shaft 114 has secured to it by means of a pin 116 a sleeve 117 to which is also connected a pin 118. The pin 118 serves as a stop to limit the movement of the rock shaft and this pin 118 contacts with a fixed 120 portion of the machine framework as at 119, see Figure 6.

125 120 designates a spring which encircles the sleeve 117, and one end of this spring bears against a fixed portion of the framework, while the opposite end is connected to a stop pin 118 so that after the shaft has been actuated the spring 120 returns the rock shaft 114 to its initial or normal position. The pin 118 serves as a stop member 130

to limit the movement of the manually actuated rock shaft and thus prevent injury to the coin mechanism and the other moving parts of the machine. Positioned beneath 5 the coin wheel is a coin chute 121 through which the coins, which serve to operate the machine, pass to a coin box (not shown).

The operation of the vending machine will now be readily apparent to those 10 skilled in this art and is as follows:

Assuming that the liquid container 2 has been filled with coffee and the liquid container 3 has been filled with cream, it will be understood that, depending upon the 15 position of the valve, one or the other of the liquid measuring chambers 24 will be filled with coffee, which passes thereinto through the passage 12, port 13 and, for example as seen in Figure 11, the port 40, 20 thence through the port 14 in the valve casting 10, the tubular member 30 and passages 26 and 23 into the measuring cup 24.

In a similar manner one of the measuring chambers 67 or 68 has been filled with 25 cream. The intending purchaser inserts a coin of the proper denomination in the coin slot 92 and this coin, if it is of the proper denomination for which the coin mechanism has been set, passes into and through the 30 coin slot 92 and into the inclined slot 95 in the coin wheel 96.

The purchaser now takes hold of the grasping handle 115 and rocks the shaft 114 in a clockwise direction, whereupon the cam 35 106, see Figure 4, will press the coin in the coin slot 95 against the plunger 98 and move it outwardly so that the coin wheel 96 together with the shaft 55 to which it is connected may rotate a quarter turn. If the 40 coin is not of the proper dimensions it will be retained in the coin chute 93 in a manner which will be clearly understood by reference to my prior patent in fraud preventative device, No. 852,111, April 30th, 1907, so 45 that when the grasping handle 115 has been actuated to rock the rock shaft 114 the cam 108 acting on the roller 109 will open the movable side 94 of the coin chute so that any coin retained therein will drop into the re- 50 turn chute 110 and pass into the receptacle 111 in a position accessible to the intending purchaser. If a coin of the proper dimensions has been inserted in the machine and the rock shaft actuated in the manner de- 55 scribed, then a quarter turn, as is evident, will be imparted to the shaft 55 which will cause the valve 78 to be rotated a quarter turn so that the cream in the measuring chamber 67, for example, see Figure 9, will 60 pass therefrom through the valves 78 and ports 76 into and through discharge pipe 87. At the same time that the valve 78 is rotating the gear 54 will have moved the gear 53 into such position that the shaft 51 has been 65 rotated one-quarter turn so that the coffee

in the measuring chamber 24, see Figure 11, will be discharged therefrom through the valve 39 and the port 16 into and through the discharge pipe 85. It will be apparent that when the liquid is being discharged 70 from one measuring chamber either in the liquid container 2 or the liquid container 3, the second measuring chamber of each container is being filled so that the machine can be operated very rapidly.

It has heretofore been proposed to construct liquid vending machines which were set into operation by the action of a coin and employing motors of various types. These devices while theoretically practicable 80 are liable to get out of order at the very time when the largest amount of sales are being made and render the machine inoperative, and if the motor is connected to all of the liquid vending machines they will all be 85 put out of commission. In accordance with my present invention the operation of the machine is manually controlled, and the construction is such that the machine is fool proof as the only thing the intending pur- 90 chasing can operate is the grasping handle 115 connected with the rock shaft 114. If a coin of the proper denomination has not passed into the coin wheel, the liquid vending mechanism cannot be operated by the 95 intending purchaser and all that he can do is to rock the shaft 114 back and forth without injury to the vending mechanism.

Special attention is directed to the construction and location of the measuring cups 100 which are surrounded by the insulating material or the temperature changing medium in the space between the inner and outer container of each liquid container unit, and the valve mechanism which controls the 105 passage of the liquid to be vended from a liquid container into the measuring cups is in close proximity to its liquid container so that the liquid in a measuring cup will be retained in a heated or cooled condition at 110 substantially the same temperature in the measuring cup as it is in the liquid container and can be maintained at such temperature until the time at which it is actually discharged from the machine.

It will now be apparent that I have devised a novel and useful construction of a liquid vending machine which embodies the features of advantage enumerated as desirable in the statement of the invention and 120 the above description, and while I have, in the present instance, shown and described a preferred embodiment thereof which will give in practice satisfactory and reliable results, it is to be understood that such embodiment is susceptible of modification in various particulars without departing from the spirit or scope of the invention or sacrificing any of its advantages.

Having thus described my invention, what 130

I claim as new and desire to secure by Letters Patent, is:—

1. In a liquid vending machine, a liquid container comprising an inner and an outer casing having a chamber between them to receive a temperature changing medium, a plurality of measuring cups in said chamber, a valve exterior of said container to alternately admit liquid from said inner casing into said cups and to alternately permit the discharge of liquid from said cups, a source of heat in proximity to said valve, and means to control said valve. 5
2. In a liquid vending machine, a container comprising an inner and an outer casing having a chamber between them to receive a temperature changing medium, measuring cups in said chamber and opening into said inner casing, a fluid tight closure for each cup to prevent liquid from said inner casing passing thereinto, a vent from each cup extending above the liquid in the inner casing, a valve constructed to permit liquid to pass from the inner casing into 10 one measuring cup while the other measuring cup is discharging and to permit one measuring cup to discharge while the other measuring cup is filling, and means to actuate said valve. 20
3. In a liquid vending machine, a container comprising an inner and an outer casing having a chamber between them to receive a temperature changing medium, a tubular fastening device to space said casings from each other and form a discharge 25 passage from the inner casing, a plurality of measuring cups carried by said casing, each cup opening into said inner casing, a fluid tight closure for each cup to prevent liquid from the inner casing passing thereinto, a valve in communication with said passage and with said measuring cups and having a discharge port, and means to actuate said valve to cause one measuring cup to empty 30 while the other measuring cup is being filled. 45
4. In a liquid vending machine, a container comprising an inner and an outer casing having a chamber between them to receive a temperature changing medium, a tubular fastening device to space said casings from each other and form a discharge 50 passage from the inner casing, a plurality of measuring cups within said chamber, each of said cups extending into said inner casing, a fluid tight closure for each cup to prevent liquid from the inner casing passing thereinto, a valve in communication with said passage and with said measuring cups and having a discharge port, and means to 55 actuate said valve to cause one measuring cup to empty while the other measuring cup is being filled. 60
5. In a liquid vending machine, a liquid container comprising an inner and an outer casing having a chamber between them to 65
- receive a temperature changing medium, a pair of measuring cups within said chamber and contributing to space said casings from each other, a closure for each cup to prevent liquid from the inner casing passing directly into each cup, a valve casing having a discharge port, a valve within said casing constructed to permit the liquid to pass from said inner casing to one of said measuring cups and to permit liquid in the other 70 measuring cup to pass at the same time to said discharge port, and means to actuate said valve. 75
6. In a liquid vending machine, a plurality of liquid containers each comprising an inner and an outer casing having a chamber to receive a temperature changing medium, a pair of measuring cups in each chamber, each of said cups extending into said inner casing, a closure for each cup to prevent liquid passing from said inner casing directly into each cup, a valve for each container constructed to permit one measuring cup to discharge while the other measuring cup is filling, intergeared shafts connected with said valves to actuate them, and means to actuate one of said shafts. 80
7. In a liquid vending machine, a liquid container comprising an inner and an outer casing having a chamber between them to receive a temperature changing medium, a tubular fastening device contributing to space said casings from each other, a valve casing connected to said fastening device and having an inlet port in communication with said fastening device, a pair of measuring cups within said chamber and in communication with said valve casing, means to prevent liquid passing from said inner casing directly into each measuring cup, a valve constructed to control the alternate filling and discharge from each measuring cup, and means to actuate said valve. 90
8. In a liquid vending machine, a liquid container comprising an inner and an outer casing having a chamber between them, to receive a temperature changing medium, a pair of measuring cups within said chamber, a closure for each cup having its inner contour controlling the capacity of its respective cup and preventing liquid from said inner casing passing directly into the upper portion of said cup, a valve controlling the admission of liquid from said inner casing to each measuring cup and controlling the discharge from each measuring cup, and means to actuate said valve to cause one cup to be filled while the other cup is being discharged. 100
9. In a liquid vending machine, a liquid container comprising an inner and an outer casing having a chamber between them to receive a temperature changing medium, a tubular fastening device passing through the bottoms of said casings, a sleeve surrounding 105
- 110
- 115
- 120
- 125
- 130

8
said device, a valve casing supported by said container in communication with said fastening device, a pair of measuring cups within said chamber and in communication with 5 said valve casing, said cups communicating with said inner casing, closures for said cups to prevent liquid passing from the inner casing directly into said cups, a valve in said casing simultaneously controlling the filling 10 of one measuring cup and the discharge from the other measuring cup, and means to actuate said valve.

10. In a liquid vending machine, a liquid container comprising an inner and an outer 15 casing having a chamber between them to receive a temperature changing medium, measuring cups in said chamber and fixedly secured to the bottoms of said casings, and opening therethrough, means to prevent 20 liquid passing from said inner casing directly into said cup, a valve supported by said container and in communication with said inner casing, and said measuring cups and having a discharge port, and means to 25 actuate said valve to cause one measuring cup to discharge while the other measuring cup is being filled.

11. In a liquid vending machine, a liquid container comprising an inner and an outer 30 casing, measuring cups within said container, closures for said cups within said inner casing, a valve carried by said container and in communication with said inner casing and with said measuring cups, and means to 35 actuate said valve to cause one cup to be filled while the other cup is being emptied, said closures being removable from within said inner casing.

12. A liquid vending machine comprising a double walled container, forming a chamber adapted to receive a temperature changing medium, a pair of measuring cups within said container, a valve carried by said chamber and communicating with the inner of 40 said double walled containers, closures for 45 said cups to prevent liquid passing from said inner container directly into said cups and controlling the communication between said inner casing and said measuring cups and the discharge from said measuring cups, 50 a source of heat beneath said container, an anti-friction bearing for said valve to prevent its binding from heat generated by said source of heat, and means to actuate said valve to cause one measuring cup to discharge while the other measuring cup is being filled.

13. In a liquid vending machine, a plurality of liquid containers, a pair of measuring cups within each container, a valve for 60 each pair of measuring cups and in communication with its respective container, a shaft connected with each valve, a gear on one valve shaft, a third shaft detachably connected with the other valve, a gear on 65 said third shaft meshing with said first gear, and means to actuate said third shaft to control said valve and to cause one measuring cup in each container to discharge while the other measuring cup in each container is 70 being filled.

JOHN FRITSCHE.
